UNITED STATES PATENT OFFICE.

MARTIN RASMUSSEN, OF RACINE, WISCONSIN.

DESIGN FOR A BROOM-CLAMP.

50,630.

Specification for Design.

Patented Apr. 17, 1917.

Application filed February 19, 1917. Serial No. 149,689. Term of patent 3½ years.

To all whom it may concern:

Be it known that I, MARTIN RASMUSSEN, a subject of the King of Denmark, residing in the city of Racine, in the county of Racine and State of Wisconsin, have invented a new, original, and ornamental Design for a Broom-Clamp, of which the following is a specification, reference being had to the accompanying drawing, forming part thereof.

The figure is an elevation of my new, original, and ornamental design for broom clamp.

I claim:

The ornamental design for broom clamp substantially as shown.

In witness whereof I hereto affix my signature.

MARTIN RASMUSSEN.
